DESIGN FOR COMBINED SUSPENDERS AND LEGGINGS

Hannah M. Seeley, San Diego, Calif.

Application February 2, 1940, Serial No. 89,956

Term of patent 14 years

To all whom it may concern:

Be it known that I, Hannah M. Seeley, a citizen of the United States, residing at San Diego, in the county of San Diego and State of California, have invented a new, original, and ornamental Design for Combined Suspenders and Leggings, of which the following is a specification, reference being had to the accompanying drawing, forming part thereof, in which

I claim:

The ornamental design for combined suspenders and leggings, as shown.

HANNAH M. SEELEY.
